UNITED STATES PATENT OFFICE.

RASMUS NIELSEN, OF TROY, NEW YORK.

ICE-SHAVING DEVICE.

No. 918,893.

Specification of Letters Patent.

Patented April 20, 1909.

Application filed March 28, 1908. Serial No. 423,939.

To all whom it may concern:

Be it known that I, RASMUS NIELSEN, a citizen of the United States, residing at Troy, in the county of Rensselaer and State 5 of New York, have invented certain new and useful Improvements in Ice-Shaving Devices, of which the following is a specification.

This invention relates to improvements in 10 a device for conveniently shaving ice, and means employed for holding a receptacle to receive the shavings.

The invention consists in providing a shaver, provided with a peculiarly arranged 15 resilient receptacle retainer to engage a receptacle to receive the shavings.

The invention also relates to improvements in the specific details of construction and arrangement of parts, which will be 20 hereinafter described and particularly pointed out in the claims.

In the drawings: Figure 1 is a perspective view of my improved shaver showing its application. Fig. 2 is a plan view. Fig. 3 is a 25 vertical central section.

1, indicates a base, formed with a handle 2. An opening 3, is formed in the base 1, and the front and rear walls thereof incline toward each other, and are connected below 30 the base by side pieces. Connected to the under side of the front wall 4, and extending beyond the bottom edge of the same is a toothed shaver or scraper 5, secured in position by a screw 6.

35 The base is provided with an outwardly extending front flange 7, from which projects a stud 8. A similar stud 9, projects upwardly from the handle where it joins the base. The end of a wire formed of spring 40 metal bears against one edge of the base at 10, and is then coiled around stud 9, and is then bent in a semi-circle 9^a, to approximately correspond to the shape of the base to a point adjacent the stud 8. The wire is 45 now coiled around stud 8, from thence it extends in semi-circular form to correspond to the opposite outline of the base. The free end of the wire passes under the semi-circular portion 9^a, and is turned upon itself to 50 form a finger piece 11. The semi-circular portion 9^a, is fixed between the studs, while the complementary semi-circular portion 10^a, is free. The semi-circular portion 10^a, of the wire readily yields when pressure is applied to the finger piece, for the insertion of a 55 glass, or other receptacle to receive the ice

shavings. The wire is retained in position by frictional contact with the post 9, and the cotter-pin 13, in an opening formed in post 8.

In use an ordinary drinking glass, or the like receptacle is best adapted in connection with my invention. Pressure is applied to the finger piece, in the direction of the arrow a, then the glass is seated on the base and between the two semi-circular portions of 60 the wire. Pressure on the finger piece is now removed and owing to the resiliency of the metal, semi-circular portion 10^a, springs back toward its normal position and the glass is tightly gripped. The glass being 65 secured to the scraper, and the open end thereof being opposite the opening 3, the ice as it is shaved is confined in the glass, when by turning over the implement with the glass, the shavings will be caught by the 70 latter. Obviously the glass can be released by applying pressure to the finger piece.

The invention is extremely simple in construction, and is well adapted for a convenient and durable domestic article. It is 80 strong; the parts are large and few, and can be readily and conveniently cleaned.

What I claim is:

1. An article of the character described, comprising a base formed with an opening, 85 a shaver adjacent the opening, and a resilient receptacle retainer secured to the base and extending entirely around the latter.

2. An article of the character described, comprising a base formed with an opening, 90 a shaver adjacent the opening, studs extending upwardly from the base, and a receptacle retainer supported by the studs, one end of the retainer being free and resilient, and adapted to be forced outwardly to receive a 95 receptacle.

3. An article of the character described, comprising a base formed with an opening, 100 a shaver adjacent the opening, studs extending upwardly from the base, and a receptacle retainer bent around the studs and being one end resilient and free, the free end being bent to form a finger piece, the portion of the retainer secured between the studs forming a rest against which a receptacle abuts when 105 the free end engages the opposite side of said receptacle.

4. An article of the character described, comprising a base formed with an opening, 110 a shaver adjacent the opening, studs extending upwardly from the base, a wire coiled around one stud and extending above and

in substantial alinement with one side the base to another stud where it is coiled and then extends above and in substantial alinement with the opposite side of the base, the latter extension being free and resilient, and means for holding the wire to the studs.

5. An article of the character described, comprising a base having an opening, a shaver adjacent the opening and a receptacle 10 retainer mounted on the base and corre-

sponding to the outline thereof, one side the retainer being stationary and the other side being free and extending under the stationary portion.

In testimony whereof I affix my signature 15 in presence of two witnesses.

RASMUS NIELSEN.
